UNITED STATES PATENT OFFICE

FRITZ STRAUB AND WALTER ANDERAU, OF BASEL, SWITZERLAND, ASSIGNEES TO
FIRM OF SOCIETY OF CHEMICAL INDUSTRY IN BASEL, OF BASEL, SWITZERLAND

AZO-DYESTUFF AND PROCESS OF MAKING SAME

No Drawing. Application filed June 10, 1930, Serial No. 460,283, and in Switzerland June 12, 1929.

This invention relates to the manufacture of new azo-dyestuffs. It comprises the process of making these dyestuffs, the new dyestuffs themselves, as well as the material dyed therewith.

According to this invention valuable azo-dyestuffs containing an azine nucleus are obtained by coupling at least one molecular proportion of a diazo-compound of the general formula

wherein R stands for an aryl residue which may contain substituents, with an azine which is obtained by treating with acids the azo-dyestuffs of the general formula

in which R_1 and R_2 stands for aryl residues which may contain substituents, one y is an OH-group and the other y a hydrogen atom, one z an SO_3H -group and the other z a hydrogen atom, the SO_3H -group and the OH-group being in meta-position to each other.

If the diazo-compounds which are to come into use derive from compounds of the general formula

in which x stands for such a group in ortho-position to the $-N=N-OH$ residue which, in combination with the azo-chromophore of the dyestuff, imparts to the latter the capability of binding metals adapted to form

lakes, and in which R stands for an aryl residue, which may contain further substituents, the azo-dyestuffs which are obtained after the coupling with the said azines may yet be treated with agents yielding metals capable of forming lakes.

Azines of the stated kind may be made from an N-substituted 2-amino-5-hydroxynaphthalene-7-sulfonic acid or from an N-substituted 2-amino-8-hydroxynaphthalene-6-sulfonic acid, by coupling a diazo-compound in an acid medium and treating with an acid the ortho-amino-azo-dyestuff thus obtained. Among other compounds the following N-substitution products of 2-amino-5-hydroxynaphthalene-7-sulfonic acid or 2-amino-8-hydroxynaphthalene-6-sulfonic acid comply with the reaction and yield azines which are useful for the manufacture of dyestuffs in accordance with the invention: N-phenyl, N-para'-tolyl, N-para'-anisidyl, N-meta'-chloro-phenyl, N-ortho'-ortho'-xylyl, N-para'-xylyl, N-ortho'-carboxyphenyl, N-meta'-carboxyphenyl, N-para'-carboxyphenyl-, N-para'-hydroxy - meta' - carboxyphenyl and N-naphthyl; also 2:2'-dinaphthyl-amine-5:5'-dihydroxy-7:7'-disulfonic acid.

The azines can be coupled with any diazo-compound. Azines which can be coupled twice, may be treated once or twice with the same or with different diazo-compounds.

The dyestuffs may be produced on the fibre, in which case it is advantageous to pad the fibre with the azine in the form of its leuco-compound and, after oxidation, to develop the dyeing with the diazo-compound.

Dyestuffs which show mordant properties can be treated in substance, in the course of their manufacture, in the dye-bath or on the fibre with an agent yielding metal, whereby

conversion into the metal compound may occur whether in acid, neutral or alkaline medium, with or without a suitable addition, and at ordinary pressure or under increased pressure. The metals which are suitable for the present process are those which can form complexes, for instance those which have the atomic weight 27 to 66, such as, for example, chromium, copper, iron, cobalt or nickel.

10 It is also possible to obtain dyestuffs containing several metals. The products of the invention may be used for dyeing wool, silk or cotton, viscose and varnishes.

15 The following example illustrates the manufacture of such azines which are being used for the production of dyestuffs in accordance with the present invention, the parts being by weight:—

To the diazo-compound from 209 parts of sulfanilic acid there are added the freshly precipitated suspension, feebly acid with mineral acid, of 362 parts of 2-ortho'-carboxy-phenylamine-5-hydroxynaphthalene-7-sulfonic acid and the mixture is stirred at the ordinary temperature until the diazo-compound has disappeared. When coupling is complete the whole is warmed on the water-bath until a sample of the dyestuff dissolved to a pure yellow solution in dilute acetic acid. By adding 20-50 parts of hydrochloric acid the formation of azine may be accelerated. When conversion is complete the liquid is made alkaline with sodium

carbonate and the sodium salt of the 2-sulfo-4-hydroxy- α - β -naphtho-8-carboxy-phenazine of the probable formula:—

is precipitated by addition of common salt. This product is an orange-brown powder, soluble in water to an orange solution and in dilute acetic acid to a clear yellow solution. Dilute hydrochloric acid produces in such a solution an orange-red precipitate. In dilute alkalies the azine dissolves to a red solution and in concentrated sulfuric acid to a green-blue solution. Alkaline reducing agents convert the product into the dihydro-azine which is soluble to a yellow solution. The azine is capable of coupling with diazo-compounds.

The reaction may be extended to the various homologues of the 2-arylaminohydroxynaphthalene-sulfonic acid series.

The following table shows the properties of some of the azines which are used for the production of dyestuffs according to the present invention:—

5	Nomenclature (Richter) and constitution	Parent material	Reactions						70
			CH ₃ COOH 10 per cent	HCl 10 per cent	Soda 10 per cent	NaOH 10 per cent	Vat NaOH	H ₂ SO ₄ concentrated	
10	(3) 2 - sulfo - 4 - hydroxy - α - β - naphtho - 10 - ethoxy - phenazine	2 - para' - ethoxyphenyl - amino - 5 - naphthol - 7 - sulfonic acid.	Orange	Red	Red	Orange	Yellow	Violet-brown.	73
15	(4) 2 - sulfo - 4 - hydroxy - α - β - naphtho - 8 - methoxyphenazine	2 - ortho' - methoxyphenylamino - 5 - naphthol - 7 - sulfonic acid	Orange	Red precipitate	Orange	Orange	Yellow	Green-blue	80
20	(5) 2 - sulfo - 4 - hydroxy - α - β - naphtho - 8:10 - dimethylphenazine	2 - ortho' - para' - dimethylphenylamino - 5 - naphthol - 7 - sulfonic acid	Brownish-orange	Blue-red	Reddish-orange	Red	Yellow	Blackish-blue-violet	83
25	(6) 2 - sulfo - 4 - hydroxy - α - β - naphtho - 9 (11) - chlorophenazine	2 - meta' - chlorophenylamino - 5 - naphthol - 7 - sulfonic acid	Orange	Brownish-red	Red	Red	Yellow	Violet	93

35									103
40									110
45									115

The following examples illustrate the manufacture and application of dyestuffs in accordance with the invention, the parts being by weight:—

Example 1

33 parts of 2-sulfo-4-hydroxy- α - β -naphtho-phenazine of the probable formula

sodium carbonate in 450 parts of water. There are then added 16 parts of sodium bicarbonate and the temperature is reduced to 5–6° C. by means of ice, whereupon the diazo-compound from 12.3 parts of ortho-anisidine is introduced. After a short time the coupling is finished and the dyestuff of the formula

65 are dissolved with aid of 5.5 parts of calcined may be filtered and dried. It is a dark pow-

der, which forms in water a brown suspension and in dilute sodium carbonate solution a violet-brown suspension. In concentrated sulfuric acid it dissolves to a blackish-green solution. It dyes wool in an acid bath brown fast tints.

If in this example, there is used instead of ortho-anisidine, an equivalent quantity of para-nitraniline there is obtained a dyestuff 10 which dyes wool red-brown. With the diazo-compound from sulfanilic acid there is obtained a red-brown dyestuff and with para-nitraniline-ortho-sulfonic acid a violet-brown dyestuff.

15

Example 2

30 parts of 2-sulfo-4-hydroxy- α - β -naphtho-phenazine are dissolved in 330 parts of water with aid of 25 parts of calcined sodium carbonate, and the solution is coupled at 8-10° C. with the diazo-compound from 22 parts of 4-nitro-2-amino-1-phenol-6-sulfonic acid. After some hours the coupling is complete 25 and the dyestuff of the formula

may be separated by salting out. It is a 40 brown powder soluble in dilute acetic acid to an orange solution. In dilute sodium carbonate solution it dissolves to blackish-brown-violet (dichroitic) solution and in concentrated sulfuric acid to a green solution. It 45 dyes wool in an acid bath blackish-green tints, which become fast blackish-violet by after-treatment with a copper salt and a dark green on treatment with a chromium salt. Cotton is dyed in a bath alkaline with sodium carbonate grey tints, which yield a fast violet on 50 after-treatment with copper. In the presence of chromium salts cotton is dyed olive-green tints.

55

Example 3

The dyestuff obtained as described in Example 2 is dissolved hot in 2000 parts of water and the solution is mixed with a solution of chromium fluoride corresponding 60 with 16 parts of Cr_2O_3 , the whole being boiled for 24 hours, water being supplied from time to time in place of that evaporated. The new chromium compound may then be salted out. When dry it is a blackish powder, soluble in 65 water to a blackish-brown-violet solution, in

sodium carbonate solution of 10 per cent. strength to a blackish-green solution and in concentrated sulfuric acid to an olive-brown solution. Wool and silk are dyed by this dyestuff in an acid bath fast green tints. Cotton and artificial silk of regenerated cellulose are dyed in a neutral bath or a bath alkaline with sodium carbonate green-grey tints which 70 equalize well.

Example 4

75

The dyestuff from 33 parts of 2-sulfo-4-hydroxy- α - β -naphtho-phenazine and 22 parts of 4-nitro-2-amino-1-phenol-6-sulfonic acid described in Example 2 is dissolved in 2000 parts of water and mixed, while hot, with 26 parts of crystallized copper sulfate. The copper compound of the dyestuff is then obtained by salting out. When dry it is a bronze powder which dissolves in water and in dilute alkalies to a red-violet solution and in concentrated sulfuric acid to a green solution. It dyes cotton and artificial silk of 80 regenerated cellulose in a bath containing Glauber's salt, which may be neutral or alkaline with sodium carbonate, violet tints.

85

If there be substituted for the 26 parts of copper sulfate an equivalent quantity of nickel sulfate there will be obtained the nickel compound similar to the copper compound. 90 This nickel compound dissolves in water to a red-violet solution, in dilute alkalies to a brown-violet solution and in concentrated sulfuric acid to a green solution, and dyes cotton in a bath containing Glauber's salt greenish-violet tints.

95

Instead of the naphtho-phenazine used in Examples 1-4 there may be used with like results the 2-sulfo-4-hydroxy- α - β -naphtho-10-tolazine. The dyestuffs are very similar in 105 tint and properties to those described.

Example 5

100

34 parts of 2-sulfo-4-hydroxy- α - β -naphtho-10-tolazine are dissolved in 300 parts of water 110 with the aid of 5.5 parts of calcined sodium carbonate and after addition of 30 parts of crystallized sodium acetate the solution is coupled with the diazo-compound from 14 parts of anthranilic acid. When coupling is 115 complete the dyestuff of the formula

115

is isolated. When dry it is a blackish powder 120 soluble in water to a brown-red solution, in

125

dilute alkalies to a red solution and in concentrated sulfuric acid to a green solution. It dyes wool in an acid bath Bordeaux-red tints which become faster when after-treated with copper; when after-chromed, the tint is a dark brown. On cotton, in presence of a chromium salt, there is obtained a brown shade.

If in this example on completion of the coupling the dyestuff is boiled with a solution of 25 parts of copper sulfate and filtered when cold, there is obtained the complex copper compound of the dyestuff. It is a dark powder which dissolves in water to a red solution, in dilute sodium carbonate solution to a blue-red solution and in concentrated sulfuric acid to a green solution. It dyes vegetable fibres in a bath containing Glauber's salt, and alkaline with sodium carbonate or neutral, violet tints.

Example 6

47 parts of 5:5'-dihydroxy-7:7'-disulfo-1:1':2':2-dinaphthazine are dissolved in 500 parts of water with aid of 10.5 parts of sodium carbonate and coupled in presence of sodium bicarbonate and sodium acetate with the diazo-compound from 44 parts of 4-nitro-1-aminobenzene-2-sulfonic acid. When coupling is complete, the dyestuff of the formula

acid. After some hours the azo-dyestuff formed of the formula

may be salted out. When dry it is a black powder, soluble in water to a blackish-green solution, in dilute alkalies to a blackish-green solution and in concentrated sulfuric acid to a green-blue solution. It dyes cotton in a neutral bath containing Glauber's salt green-grey tints which become fast reddish-grey when after-treated with copper. In presence of chromium salts it dyes cotton grey-green. In an acid bath it dyes wool a blackish-green, which becomes faster when after-chromed; when treated with copper the dyeing becomes grey.

Example 8

The copper complex compound of the dyestuff of Example 7 is obtained by heating the dyestuff formed on completion of the coupling with an ammoniacal solution of copper oxide made from 50 parts of crystallized copper sulfate. This complex copper compound is a black powder soluble in water to a reddish-violet solution, in dilute sodium carbonate solution to a blue-violet solution and in concentrated sulfuric acid to a blue-green solution. It dyes cotton and artificial silk of regenerated cellulose in a bath containing Glauber's salt, and neutral or alkaline, very fast grey equal tints. It dyes wool in an acid bath grey tints.

Example 9

The dyestuff of Example 7 obtained from 47 parts of 5:5'-dihydroxy-7:7'-disulfo-1:1':2':2-dinaphthazine and 45 parts of 4-nitro-2-amino-1-phenol-6-sulfonic acid is dissolved in 4000 parts of water and the solution is boiled for several hours with a solution of chromium fluoride made from 20 parts of Cr_2O_3 . In this manner the chromium compound of the dyestuff is obtained. It is soluble in water to a grey blue solution, in dilute alkalies to a green blue solution and in concentrated sulfuric acid to a green solution. Cotton and artificial silk of regenerated cellulose are dyed in a neutral or alkaline bath containing Glauber's salt very level

is isolated by salting out and dried. It is a dark powder soluble in water to a blue-red solution; in dilute sodium carbonate solution to a violet solution and in dilute caustic soda solution to a blue-violet solution. In concentrated sulfuric acid it dissolves to a green solution. It dyes wool in an acid bath reddish-brown tints and cotton in a bath containing Glauber's salt and alkaline with sodium carbonate red-violet tints.

Example 7

47 parts of 5:5'-dihydroxy-7:7'-disulfo-1:1':2':2-dinaphthazine are dissolved in 400 parts of water with aid of 40 parts of calcined sodium carbonate, and the solution is coupled with the diazo-compound from 45 parts of 4-nitro-2-amino-1-phenol-6-sulfonic

greenish-grey tints. On wool in an acid bath the dyestuff yields green tints.

In place of the 4-nitro-2-amino-1-phenol-6-sulfonic acid used as the diazotizing component in Example 7-9, there may be used 4-nitro-2-amino-1-phenol. In this case dyestuffs are obtained which have substantially the same properties and tints as those of the dyestuffs described above. Their solubility is somewhat smaller. Instead of the nitro-aminophenolsulfonic acid there may be used 4-chloro-2-amino-1-phenol-6-sulfonic acid.

Example 10

15

A grounding bath is prepared from 18 grams of 5:5'-dihydroxy-7:7'-disulfo-1:1':2':2'-dinaphthazine, 50 cc. of caustic soda solution of 40 per cent. strength per litre of liquor, and the warm bath is reduced to dihydroazine by means of 5 grams of sodium hydrosulfite. Cotton is handled under the liquor in this bath at room temperature for $\frac{1}{4}$ hour. It is then rinsed, whereby the azine is re-oxidized. Development may then follow in known manner by means of a neutralized diazo-compound. With para-nitrodiazobenzene there is obtained a brown-olive tint, while with diazotized 2-amino-4-chlorobenzene-1:1'-phenylether an olive-brown dyeing is obtained.

What we claim is:—

1. In the manufacture of metalliferous azo-dyestuffs containing the azine nucleus, the step which comprises coupling at least one molecular proportion of a diazo-compound of the general formula

40

wherein R stands for a benzene radicle and x for a lake-forming group in ortho-position to the azo-group, with the azines which are obtained by treating with acids the azo-dyestuffs of the general formula

50

in which R_1 and R_2 stand for aryl radicles of the benzene and naphthalene series, one y is an OH-group and the other y a hydrogen atom, one z an SO_3H -group and the other z a hydrogen atom, the SO_3H -group and the OH-group being in meta-position to each other.

2. In the manufacture of metalliferous azo-dyestuffs containing the azine nucleus, the step which comprises coupling at least

one molecular proportion of a diazo-compound of the general formula

wherein x stands for a lake-forming group in ortho-position to the azo-group and R stands for a benzene radicle with the azines which are obtained by treating with acids the azo-dyestuffs of the general formula

in which R_1 and R_2 stand for aryl radicles of the benzene and naphthalene series.

3. In the manufacture of metalliferous azo-dyestuffs containing the azine nucleus, the step which comprises coupling at least one molecular proportion of a diazo-compound of the general formula

wherein x stands for a lake-forming group in ortho-position to the azo-group, and R stands for a benzene radicle with the azines which are obtained by treating with acids the azo-dyestuffs of the general formula

in which R_1 stands for an aryl radicle of the benzene and naphthalene series.

4. In the manufacture of metalliferous azo-dyestuffs containing the azine nucleus, the step which comprises coupling at least one molecular proportion of a diazo-compound of the general formula

wherein R stands for a benzene radicle and the OH-group stands in ortho-position to the azo-group, with the azines which are obtained by treating with acids the azo-dyestuffs of the general formula

in which R_1 stands for an aryl radicle of the benzene and naphthalene series.

5. In the manufacture of metalliferous azo-dyestuffs containing the azine nucleus, the step which comprises coupling two molecular

proportions of a diazo-compound of the general formula

5 wherein R stands for a benzene radicle and the OH-group stands in ortho-position to the azo-group with the azines which are obtained by treating with acids the azo-dyestuffs of the general formula

15 in which R₁ stands for an aryl radicle of the benzene and naphthalene series.

20 6. In the manufacture of a metalliferous azo-dyestuff containing the azine nucleus, the step which comprises coupling two molecular proportions of diazotized 4-nitro-2-amino-1-phenol-6-sulfonic acid of the formula

30 with the azine which is obtained by treating with acids the azo-dyestuff of the formula

40 7. In the manufacture of metalliferous azo-dyestuffs containing the azine nucleus, the step which comprises treating with an agent yielding metal capable of forming lakes with the lake-forming groups of the azo-dyestuffs, the azo-dyestuffs which are obtained by coupling at least one molecular proportion of a diazo-compound of the general formula

45 50 wherein R stands for a benzene radicle and x for a lake-forming group in ortho-position to the azo-group, with the azines which themselves are formed by treating with acids the azo-dyestuffs of the general formula

60 wherein R₁ and R₂ stand for aryl radicles of the benzene and naphthalene series, one y is an OH-group and the other y a hydrogen atom, one z an SO₃H-group and the other z a hydrogen atom, the SO₃H-group and the

OH-group being in meta position to each other.

8. In the manufacture of metalliferous azo-dyestuffs containing the azine nucleus, the step which comprises treating with an agent yielding metal capable of forming lakes with the lake-forming groups of the azo-dyestuffs, the azo-dyestuffs which are obtained by coupling at least one molecular proportion of a diazo-compound of the general formula

70 wherein R stands for a benzene radicle and x for a lake-forming group in ortho position to the azo-group, with the azines which themselves are formed by treating with acids the azo-dyestuffs of the general formula

80 wherein R₁ and R₂ stand for aryl radicles of the benzene and naphthalene series.

9. In the manufacture of metalliferous azo-dyestuffs containing the azine nucleus, the step which comprises treating with an agent yielding metal capable of forming lakes with the lake-forming groups of the azo-dyestuffs, the azo-dyestuffs which are obtained by coupling at least one molecular proportion of a diazo-compound of the general formula

95 wherein R stands for a benzene radicle and x for a lake-forming group in ortho-position to the azo-group, with the azines which themselves are formed by treating with acids the azo-dyestuffs of the general formula

105 wherein R₁ stands for an aryl radicle of the benzene and naphthalene series.

110 10. In the manufacture of metalliferous azo-dyestuffs containing the azine nucleus, the step which comprises treating with an agent yielding metal of the atomic weight 120 27 to 66 capable of forming lakes with the lake-forming groups of the azo-dyestuffs, the azo-dyestuffs which are obtained by coupling at least one molecular proportion of a diazo-compound of the general formula

115 wherein R stands for a benzene radicle and x for a lake-forming group in ortho-position

to the azo-group, with the azines which themselves are formed by treating with acids the azo-dyestuffs of the general formula

6

10

wherein R_1 stands for an aryl radicle of the benzene and naphthalene series.

11. In the manufacture of metalliferous azo-dyestuffs containing the azine nucleus, the step which comprises treating with an agent yielding metal of the atomic weight 52 to 66 capable of forming lakes with the lake-forming groups of the azo-dyestuffs, the azo-dyestuffs which are obtained by coupling at least one molecular proportion of a diazo-compound of the general formula

25

wherein R stands for a benzene radicle and x for a lake-forming group in ortho-position to the azo-group, with the azines which are formed by treating with acids the azo-dyestuffs of the general formula

35

wherein R_1 stands for an aryl radicle of the benzene and naphthalene series.

12. In the manufacture of metalliferous azo-dyestuffs containing the azine nucleus, the step which comprises treating with an agent yielding metal of the atomic weight 52 to 56 capable of forming lakes with the lake-forming groups of the azo-dyestuffs, the azo-dyestuffs which are obtained by coupling at least one molecular proportion of a diazo-compound of the general formula

50

wherein R stands for a benzene radicle and x for a lake-forming group in ortho-position to the azo-group, with the azines which are formed by treating with acids the azo-dyestuffs of the general formula

60

wherein R_1 stands for an aryl radicle of the benzene and naphthalene series.

13. In the manufacture of metalliferous azo-dyestuffs containing the azine nucleus, the step which comprises treating with an agent yielding metal of the atomic weight 52 to 56 capable of forming lakes with the lake-forming groups of the azo-dyestuffs, the azo-dyestuffs which are obtained by coupling two molecular proportions of a diazo-compound of the general formula

70

wherein R stands for a benzene radicle and the OH-group stands in ortho-position to the azo-groups with the azines which are formed by treating with acids the azo-dyestuffs of the general formula

80

85

wherein R_1 stands for an aryl radicle of the benzene and naphthalene series.

14. In the manufacture of a chromiferous azo-dyestuff containing the azine nucleus, the step which comprises treating with an agent yielding chromium the azo-dyestuff which is obtained by coupling two molecular proportions of diazotized 4-nitro-2-amino-1-phenol-6-sulfonic acid of the formula

95

100

with the azine which itself is formed by treating with acids the azo-dyestuff of the formula

110

115

15. Process for the manufacture of metalliferous azo-dyestuffs containing the azine nucleus, consisting in coupling at least one molecular proportion of a diazo-compound of the general formula

120

125

wherein R stands for a benzene radicle, and x for a lake-forming group in ortho-position to the azo-group with the azines which are

130

formed by treating with acids the azo-dyestuffs of the general formula

10 wherein R_1 and R_2 stand for aryl radicles of the benzene and naphthalene series, one y is an OH-group and the other y a hydrogen atom, one z an SO_3H -group and the other z a hydrogen atom, the SO_3H -group and the 15 OH-group being in meta-position to each other, and then treating the azo-dyestuffs containing the azine nucleus thus obtained with agents yielding metal capable of forming lakes with the lake-forming groups of the azo-dyestuffs.

20 16. Process for the manufacture of metal-liferous azo-dyestuffs containing the azine nucleus, consisting in coupling at least one molecular proportion of a diazo-compound of the general formula

wherein R stands for a benzene radicle, and x for a lake-forming group in ortho-position 30 to the azo-group, with the azines which are formed by treating with acids the azo-dyestuffs of the general formula

40 wherein R_1 and R_2 stand for aryl radicles of the benzene and naphthalene series, and then treating the azo-dyestuffs containing the azine nucleus thus obtained with agents yielding metal capable of forming lakes with the lake-forming groups of the azo-dyestuffs.

45 17. Process for the manufacture of metal-liferous azo-dyestuffs containing the azine nucleus, consisting in coupling at least one molecular proportion of a diazo-compound of the general formula

50 wherein R stands for a benzene radicle, and x for a lake-forming group in ortho-position to the azo-group, with the azines which are formed by treating with acids the azo-dyestuffs of the general formula

wherein R_1 stands for an aryl radicle of the 55 benzene and naphthalene series, and then

treating the azo-dyestuffs containing the azine nucleus thus obtained with agents yielding metal capable of forming lakes with the lake-forming groups of the azo-dyestuffs.

18. Process for the manufacture of metal-liferous azo-dyestuffs containing the azine nucleus, consisting in coupling at least one molecular proportion of a diazo-compound of the general formula

70 wherein R stands for a benzene radicle, and x for a lake-forming group in ortho-position to the azo-group, with the azines which are formed by treating with acids the azo-dyestuffs of the general formula

80 wherein R_1 stands for an aryl radicle of the benzene and naphthalene series, and then 90 treating the azo-dyestuffs containing the azine nucleus thus obtained with agents yielding metal of the atomic weight 27 to 66 capable of forming lakes with the lake-forming groups of the azo-dyestuffs.

95 19. Process for the manufacture of metal-liferous azo-dyestuffs containing the azine nucleus, consisting in coupling at least one molecular proportion of a diazo-compound of the general formula

100 wherein R stands for a benzene radicle, and x for a lake-forming group in ortho-position to the azo-group, with the azines which are formed by treating with acids the azo-dyestuffs of the general formula

115 wherein R_1 stands for an aryl radicle of the benzene and naphthalene series, and then 120 treating the azo-dyestuffs containing the azine nucleus thus obtained with agents yielding metal of the atomic weight 52 to 66 capable of forming lakes with the lake-forming groups of the azo-dyestuffs.

125 20. Process for the manufacture of metal-liferous azo-dyestuffs containing the azine nucleus, consisting in coupling at least one molecular proportion of a diazo-compound of the general formula

130 wherein R stands for a benzene radicle, and x for a lake-forming group in ortho-position

to the azo-group, with the azines which are formed by treating with acids the azo-dyestuffs of the general formula

10 wherein R₁ stands for an aryl radicle of the benzene and naphthalene series, and then treating the azo-dyestuffs containing the azine nucleus thus obtained with agents yielding metal of the atomic weight 52 to 56 capable of forming lakes with the lake-forming groups of the azo-dyestuffs.

15 21. Process for the manufacture of metaliferous azo-dyestuffs containing the azine nucleus, consisting in coupling two molecular proportions of a diazo-compound of the general formula

25 25 wherein R stands for a benzene radicle and the OH-group stands in ortho-position to the azo-group, with the azines which are formed by treating with acids the azo-dyestuffs of the general formula

35 40 wherein R₁ stands for an aryl radicle of the benzene and naphthalene series, and then treating the azo-dyestuffs containing the azine nucleus thus obtained with agents yielding metal of the atomic weight 52 to 56 capable of forming lakes with the lake-forming groups of the azo-dyestuffs.

45 22. Process for the manufacture of a chromiferous azo-dyestuff containing the azine nucleus, consisting in coupling two molecular proportions of diazotized 4-nitro-2-amino-1-phenol-6-sulfonic acid of the formula

55 55 with the azine which is formed by treating the azo-dyestuff of the formula

65 65 with acids, and then treating the azo-dyestuff

containing the azine nucleus thus obtained with an agent yielding chromium.

70 23. As new products the metal compounds of the azo-dyestuffs containing the azine nucleus, which azo-dyestuffs are obtained by coupling at least one molecular proportion of a diazo-compound of the general formula

80 80 wherein R stands for a benzene radicle, and x for a lake-forming group in ortho-position to the azo-group, with the azines which themselves are formed by treating with acids the azo-dyestuffs of the general formula

90 90 wherein R₁ and R₂ stand for aryl radicles of the benzene and naphthalene series, one y is an OH-group and the other y a hydrogen atom, one z an SO₃H-group and the other z a hydrogen atom, the SO₃H-group and the OH-group being in meta-position to each other, which products form black to brown 95 powders which dissolve in concentrated sulfuric acid to blue-green to green to olive-brown solutions, dyeing vegetable and animal fibres violet to green to grey tints.

95 24. As new products the metal compounds of the azo-dyestuffs containing the azine nucleus, which azo-dyestuffs are obtained by coupling at least one molecular proportion of a diazo-compound of the general formula

105 105 wherein R stands for a benzene radicle and x for a lake-forming group in ortho-position to the azo-group, with the azines which themselves are formed by treating with acids the azo-dyestuffs of the general formula

115 115 wherein R₁ and R₂ stand for aryl radicles of the benzene and naphthalene series, which products form black to brown powders which dissolve in concentrated sulfuric acid to blue-green to green to olive-brown solutions, dyeing vegetable and animal fibres violet to green to grey tints.

120 120 25. As new products the metal compounds of the azo-dyestuffs containing the azine nucleus, which azo-dyestuffs are obtained by

coupling at least one molecular proportion of a diazo-compound of the general formula

wherein R stands for a benzene radicle, and α for a lake-forming group in ortho-position to the azo-group, with the azines which themselves are formed by treating with acids the azo-dyestuffs of the general formula

wherein R_1 stands for an aryl radicle of the benzene and naphthalene series, which products form black to brown powders which dissolve in concentrated sulfuric acid to blue-green to green to olive-brown solutions, dyeing vegetable and animal fibres violet to green to grey tints.

26. As new products the metal compounds of the azo-dyestuffs containing the azine nucleus and metals of the atomic weight of 27 to 66 capable of forming lakes with the lake-forming groups of the azo-dyestuffs, which azo-dyestuffs are obtained by coupling two molecular proportions of a diazo-compound of the general formula

wherein R stands for a benzene radicle, and α for a lake-forming group in ortho-position to the azo-group, with the azines which themselves are formed by treating with acids the azo-dyestuffs of the general formula

wherein R_1 stands for an aryl radicle of the benzene and naphthalene series, which products form black to brown powders which dissolve in concentrated sulfuric acid to blue-green to green to olive-brown solutions, dyeing vegetable and animal fibres violet to green to grey tints.

27. As new products the metal compounds of the azo-dyestuffs containing the azine nucleus and metals of the atomic weight of 52 to 66 capable of forming lakes with the lake-forming groups of the azo-dyestuffs, which azo-dyestuffs are obtained by coupling two molecular proportions of a diazo-compound of the general formula

wherein R stands for a benzene radicle, and

α for a lake-forming group in ortho-position to the azo-group, with the azines which themselves are formed by treating with acids the azo-dyestuffs of the general formula

wherein R_1 stands for an aryl radicle of the benzene and naphthalene series, which products form black to brown powders which dissolve in concentrated sulfuric acid to blue-green to green to olive-brown solutions, dyeing vegetable and animal fibres violet to green to grey tints.

28. As new products the metal compounds of the azo-dyestuffs containing the azine nucleus and metals of the atomic weight of 52 to 56 capable of forming lakes with the lake-forming groups of the azo-dyestuffs, which azo-dyestuffs are obtained from coupling two molecular proportions of a diazo-compound of the general formula

wherein R stands for a benzene radicle, and α for a lake-forming group in ortho-position to the azo-group, with the azines which themselves are formed by treating with acids the azo-dyestuffs of the general formula

wherein R_1 stands for an aryl radicle of the benzene and naphthalene series, which products form black to brown powders which dissolve in concentrated sulfuric acid to blue-green to green to olive-brown solutions, dyeing vegetable and animal fibres violet to green to grey tints.

29. As new products the metal compounds of the azo-dyestuffs containing the azine nucleus and metals of the atomic weight of 52 to 56 capable of forming lakes with the lake-forming groups of the azo-dyestuffs, which azo-dyestuffs are obtained by coupling two molecular proportions of a diazo-compound of the general formula

wherein R stands for a benzene radicle, and the OH-group in ortho-position to the azo-group, with the azines which themselves are formed by treating with acids the azo-dye-

stuffs of the general formula

- wherein R_1 stands for an aryl radicle of the benzene and naphthalene series, which products form black to brown powders which dissolve in concentrated sulfuric acid to blue-green to green to olive-brown solutions, dyeing vegetable and animal fibres violet to green to grey tints.
- 10 30. As a new product the chromium compound of the azo-dyestuff containing the azine nucleus, which azo-dyestuff is obtained by coupling two molecular proportions of diazotized 4-nitro-2-amino-1-phenol-6-sulfonic acid of the formula
- 20

- with the azine which is itself formed by treating the azo-dyestuff of the formula
- 30

- with acids, which product forms a black powder which dissolves in concentrated sulfuric acid to a green solution, dyeing the vegetable and animal fibres green-grey to green tints.

In witness whereof we have hereunto signed our names this 31st day of May, 1930.

FRITZ STRAUB.
WALTER ANDERAU.
